UNITED STATES PATENT OFFICE.

LOUIS STOCK, OF COLUMBUS, OHIO.

MACHINE FOR PASTING, CUTTING, AND TRIMMING WALL-PAPER.

SPECIFICATION forming part of Letters Patent No. 479,473, dated July 26, 1892.

Application filed May 15, 1891. Serial No. 392,814. (No model.)

To all whom it may concern:

Be it known that I, LOUIS STOCK, a citizen of the United States, residing at Columbus, in the county of Franklin and State of Ohio, have 5 invented a certain new and useful Improvement in Machines for Pasting, Cutting, and Trimming Wall-Paper, of which the following is a specification.

My invention relates to machines for trimming, cutting, and pasting wall-paper; and the objects of my invention are to provide a superior device of this character by means of which the pasting, trimming, and the cutting of the paper into lengths may be rapidly and 15 effectively accomplished, to produce said device in a simple and reliable form, and to produce improvements in details of construction, which will be more fully pointed out hereinafter. These objects I accomplish in the manner illustrated in the accompanying drawings, in which—

Figure 1 is a side elevation of my improved machine. Fig. 2 is a central longitudinal section of the same. Fig. 3 is a plan view on a 25 smaller scale than that shown in Figs. 1 and 2, and Fig. 4 is a longitudinal section of a portion of the paste-roll.

Similar letters refer to similar parts throughout the several views.

30 *a* represents a tank or paste-reservoir, which is preferably of an oblong form and has its upper side open. Rising from the opposite sides of the forward portion of the paste-tank *a* and secured thereto are two correspondingly-shaped frames *a'*. The forward frame-arms *a²* of said frames *a'* extend, as shown, upwardly and forwardly, and have journaled between their upper and outer ends the shaft or spindle of a horizontal reel *b*. On each 40 end of this reel, within the frame-arms *a²*, is a metallic disk *b'*.

a³ represents the rear standards of the frame, which extend upwardly from opposite sides and at opposite points of the tank *a*, said 45 frame-arms *a³* being of greater height than the arms *a²*. The central portion of each of the arms *a³* is connected by an arm *a⁴* with the upper end of the arm *a²* of the corresponding frame side.

50 Journaled longitudinally within the rear half of the tank *a*, in rear of the center of the width thereof, is a paste cylinder or roll *c*,

which, as shown in the drawings, is mounted upon a shaft *c'*, which extends longitudinally through the center of said paste-cylinder, said 55 shaft bearing in suitable internal disks *c²*, which are rigidly supported within the cylinder. The periphery of this cylinder or roll *c* is covered by a suitable cloth strip *c³*, said cloth strip being secured thereon by having 60 its ends tucked into the open ends of the cylinder *c*, where they are securely fastened by the insertion within the ends of said cylinder of plug-rings *c⁴*, which are of such size as to enter the ends of the cylinder and press the 65 inturned ends of the cloth *c³* loosely against the inner surface of the cylinder. Above the paste-tank the arms *a³* are provided with a slight forward bend, as indicated at *a⁵*, and from said forwardly-bent portions extend rear- 70 wardly short bearing-arms *d*, the inner ends of which are pivotally connected with said arms *a⁵* and the outer ends of which are in vertical alignment with the shaft of the paste-cylinder and form journal-bearings for the 75 shaft *d'* of a horizontal roll *d²*, the periphery of which is normally in frictional contact with and rests upon the upper side of the cloth-covered paste-roll *c*. Each of the bearing-arms *d* has projecting from its forward end 80 portion a catch-lug *d⁴*. Above the bend *a⁵* each of the arms *a³* has pivotally connected therewith the inner end of a rearwardly-extending catch-hook *d⁵*.

Journaled between the frame-arms *a³*, above 85 the pivot-points of the catch-hooks *d⁵*, are the ends of a roller-shaft *d⁶*, upon which is mounted a roller *d⁷*, of somewhat smaller circumference than the roller *d²*, from which said roller *d⁶* is separated, as shown. One of the outer 90 ends of the shaft *d⁶* is provided with a crank-arm *d⁷*. From the journal-points of the shaft *d⁶* the frame-arms *a³* extend upwardly and are inclined slightly forward. Between the upper ends of the arms *a³* is journaled a shaft *e*, upon 95 which is mounted a suitable roller *e'*. From the rear side of each of the arms *a³*, at a point opposite the shaft *d⁶*, extends outwardly from said arms *a³* a short arm *a⁶*, said arms *a⁶* extending to the periphery of the roller *d⁶* and 100 each having adjustably secured to the outer end thereof by a thumb-screw *e²* a short scraping-plate *e³*, extending over the ends of the roll *d⁶*.

Extending between the cross-arms a^4 is a rod or bar f , which, as shown, is of a hexagonal form in cross-section. This hexagonal rod f is clamped by the jaws of two or more 5 clutches f' , each of these clutches consisting of two arms $f^2 f^3$, which are hinged or fulcrumed at f^4 . The forward ends of these clutch-arms are bowed outwardly from each other, as shown, while the rear ends or jaws 10 $f^5 f^6$ of said arms are adapted to bear against each other, as shown, each of said jaws being provided with a half-hexagonal recess in its clamping-face, which receives one-half of the hexagonal rod f . The jaws are normally 15 clamped upon said rod f by the action of the approximately V-shaped spring-strip f^7 , which is inserted between the flaring fingers or forward ends of the arms $f^2 f^3$, said spring having its ends secured to the inner sides and outer 20 end portions of said arms $f^2 f^3$. The upper jaw f^6 of the clutch f' is extended upwardly, as shown, said upwardly-extending portion having pivoted thereto an arm g , which is approximately in the form of a bell-crank lever. The 25 upwardly-extending portion of said bell-crank arm g has journaled between the bifurcated upper end thereof a circular trimming-knife or disk g' , which is provided with sharpened edges, as shown. The forwardly-extending 30 portion of the arm g has passing through its outer end portion a set-screw k , the lower end of which bears upon a spring-strip k' , one end of said spring-strip being secured upon a shank of the jaw f^6 at the base of its upward 35 extension and the remaining end of said spring-strip bearing upon the upper side of the upper clutch-arm f^3 near the outer end thereof. Each of the frame-arms a^4 has formed therewith an upwardly-extending 40 branch arm i , said branch i projecting from that portion of the arm a^4 to which is secured the rod f .

i^2 represents a bracket or bar, having its ends bent downward at right angles with its 45 central portion, said downwardly-bent end portions being pivotally connected with the upper ends of the arms i on the opposite sides of the frame. The horizontal portion i^3 of the bracket i^2 passes loosely through the 50 body of a sliding knife-supporting bar i^4 . This knife-supporting bar i^4 is provided with a forwardly-projecting head or finger-piece i^5 , while its remaining end portion on the opposite side of the bracket i^2 is inclined 55 from the body of said knife-bar, said inclined portion being bifurcated, as shown, and having pivoted between the arms thereof a cutting-disk or knife-wheel i^6 .

As shown in the drawings, I preferably provide the paste-tank a with a partition, as indicated at a^7 , said partition extending throughout the length of said tank on the rear side of the paste-roll, thus forming a separate compartment a^8 .

65 The operation of my machine is as follows: A roll m of wall-paper to be utilized is wound, as shown, upon the roll b between the disks

b' thereof, the latter serving as end bearings for the roll. From the under side of the roll of paper m the paper is carried to and inserted between the paste-roll c and feeding-roll d^2 , then carried about the rear side of the latter and inward about the front side of the roll d^6 , from which it may be pulled upwardly by a person standing upon a suitable elevation. As indicated at n , the tank a is partially filled with ordinary liquid paste. Pulling upon the upper end of the paper m will result, through the friction between the paper and rolls, of a rotation of the two rolls d^6 and d^2 , when the frictional contact of the latter with the paste-roll will operate to rotate said paste-roll. As the paper is thus drawn from the rolls it is obvious that the entire width of the sheet is brought into contact with the paste upon the periphery of the roll c , said paste being accumulated thereon by the rotation of said roll within the paste n . In order to trim or cut from the paper the unprinted edges thereof, the clutches f' are turned upward to such position as to impart the necessary inclination to the knife-arms g required to bring the cutting-edges of the knives g' into contact with the paper m , which is on the roll d^6 . The degree of pressure of the knives g' against the paper and roll d^6 may be increased or decreased by turning the set-screw k , so as to increase or decrease the pressure of the spring-strip k' . It is obvious that any desired number of the clutches f' may be employed and that they may be located at the desired points upon the rod f , thus admitting of strips of paper being cut into different widths, as desired. In order to throw the knives g' out of engagement with the paper and roll d^6 , the clutch-arms $f^2 f^3$ may be clamped toward each other sufficiently to admit of the forward ends of the clutches being turned downward and the knife arm or bar g thereof being thereby carried forward. When a strip of paper of sufficient length has been pasted and trimmed, as hereinbefore described, a pressure upon the handle i^5 of the knife-bar i^4 will result in a forward movement of the bracket i^2 upon its pivotal connection with the arms i and a resulting contact of the sharpened edge of the knife-disk i^6 with the forward and upper side of the roll d^6 or the paper thereon. By sliding the knife-bar i^4 horizontally upon the portion i^3 of the bracket i^2 it will be seen that the knife-disk i^6 will be made to rotate and travel transversely across the paper m and result in a severing of the latter at the point of contact with said knife. It will thus be seen that the paper may be pasted, pulled upward between the rolls, trimmed, and severed into the desired lengths by my machine.

In order to prevent the accumulation of paste upon the end portions of the periphery of the roll d^6 and prevent the trimmed edges of the paper which are severed by the knives g' from becoming pasted thereto, I employ the scraping-plates e^3 , which are supported,

as hereinbefore described, upon the ends of the arms a^6 . If desired, I may rotate the rolls by turning the crank d^7 , this method of drawing the paper through the rolls being preferable where short pieces of paper are to be pasted or trimmed.

When desired, I may elevate the roll d^2 from contact with the paste-roll by causing the lugs d^4 of the bearing-arms d to engage 10 with the hook end of the catch d^3 .

In case it is desired to prepare paper for papering a ceiling, it is obvious that the paper m may be drawn upward over the upper roll e' and thence forwardly, where it will be 15 supported in the proper position for uniting with the ceiling.

The compartment a^8 of the tank a will serve as a receptacle for the trimmings which fall from the roll d^6 .

From the construction herein shown and described it will be seen that the process of papering walls and ceilings will be greatly facilitated by the use of my device.

Having now fully described my invention, 25 what I claim, and desire to secure by Letters Patent, is—

1. In a wall-paper-preparing machine, the combination, with a paste-tank a , a roll-carrying frame arising therefrom, and a paper- 30 reel journaled in said frame, of a paste-roll journaled in said tank, a feed-roll d^2 , movably journaled, as described, above said paste-roll,

and a roll d^6 , journaled above said feed-roll, substantially as described.

2. In a wall-paper-preparing machine, the 35 combination, with a paste-tank a , a roll-carrying frame arising therefrom, a paper-reel journaled in said frame, and a paste-roll journaled in said tank, of a feed-roll d^2 , movably journaled, as described, above said paste-roll, 40 a roll d^6 , journaled above said feed-roll, and one or more trimming-wheels g' , having their cutting - edges adjustably supported against the periphery of the roll d^6 , substantially as and for the purpose specified. 45

3. In a wall-paper-preparing machine, the combination, with a paste-tank a , a roll-carrying frame arising therefrom, a paper-reel journaled in said frame, and a paste - roll journaled in said tank, of a feed-roll d^2 , mov- 50 ably journaled, as described, above said paste-roll, a roll d^6 , journaled above said feed-roll, the hinged bracket i^2 , rising from the upper portion of the frame, a horizontally-sliding knife-block on said bracket, and a cutting 55 disk or knife supported thereby, said disk being adapted to be made to bear upon the periphery of the roll d^6 , substantially as and for the purpose specified.

LOUIS STOCK.

In presence of—

E. E. BBAGG,
C. C. SHEPHERD.
